UNITED STATES PATENT OFFICE

2,120,606

FASTENER

Treffle E. Fournier, Fitchburg, Mass.

Application September 15, 1936, Serial No. 100,933

1 Claim. (Cl. 292—62)

This invention relates to improvements in means for fastening and securing window screens or storm windows to window casings and the primary object of the invention is to provide complementary interlocking fixtures which when applied to the window sash, screen, and storm window, respectively, enable the screen and storm windows to be interchangeably placed on the sash in proper and intended position whenever desired and without use of tools or any major alterations in sash, screen or window.

A further object of the invention is to provide interlocking fixtures which are substantially permanent when once fastened to the window casing and to the screen and storm window with which they are to be used.

An additional object of the invention is to provide a spring locking device for securely fastening and holding the window or screen in place by spring tension.

With the above object in view my invention resides in the novel construction, arrangement and combination of parts hereinafter more fully described with reference to the accompanying drawings wherein:

Figure 1 is a plan view from the inside of a window casing and screen provided with interlocking fixtures in accordance with the present invention.

Figure 2 is a plan view of one of the side frames of the window casing showing keeper plates with arcuate cam slots.

Figure 3 is a view similar to Figure 1 but showing the screen replaced by a storm window.

Figure 4 is a view in front elevation of a side frame of a window casing showing a keeper plate with an angular cam slot.

Figure 5 is a vertical central section of the part shown in Figure 4.

Figure 6 is a detail view of the latch unit to be affixed to the screen or storm window.

Figure 7 is a sectional view of adjacent frames of window casings and screens equipped with and secured together by the improved fastener, the parts of which are clearly shown.

For the purposes of this invention, the window casing 1 is provided at diametrically opposite points near the top and bottom of the side frames 2 with recesses 3 as shown in Figures 1 and 5. Over each recess is placed a keeper plate 4 fastened to the casing by screws 5. The portion of the plate overlying the recess is cut out to provide a cam edge 6 and stop slot 7. The fastening or latching elements which engage the keeper plate 4 are carried respectively by the particular screen

8 and storm window 9 to be set in place against or within the window casing. To this end, each side frame 10 of the screen is provided with an opening or recess 11 so located therein as to be positioned properly adjacent the window casing recess 3 when the screen is in place against the casing as shown in Figure 7. Disposed over each recess 11 and fastened to the screen frame by screws or other suitable fasteners is a cover plate 12 for a cup 13, the latter being housed within 10 and snugly fitting the recess in the manner illustrated. A comparatively short pull rod or pin 14 extends into the cup through a central opening in the cover plate and at its inner end is connected with a disc or washer 15 contacting the 15 sides of the cup and serving as a cross-head or guide for steadyng the rod in its movement inwardly and outwardly of the cup. Mounted on the outer end of the pull rod and turning about the axis of the latter is a keeper engaging element comprising a flat plate having a rounded nose latch portion 16 and a reduced portion 17, the latter serving as a single hold or grip and being curved as shown to accommodate the finger. Rod 14 may be either fixed to the keeper engaging element to turn therewith or the said element may be loose on the rod to turn freely thereon. Concealed within the cup and encircling the pull rod with one end bearing against the disc and the other end bearing against the cover 20 plate is a coil spring 18. This spring is tensioned to expand between the cover plate and the disc and normally holds the rod well within the cup with the disc bearing end thereof substantially at the bottom of the cup and the latch bearing 25 end close to the cover plate. Thus, in order to fasten the screen to the casing, the pull rod is necessarily moved outwardly to align the latch element with the cam slot of the keeper and this movement is opposed by the resistance of the 30 spring, which spring resistance is increased in proportion to the spring compression. The spring resistance is overcome in the first instance by the pull of the finger against part 17 until the latch element is turned to cause part 16 to enter the 35 keeper slot and bear against the low portion of the cam edge 16. As the latch travels over the high part of the cam edge, the outward movement of the pull rod continues with further compression of the spring until the latch element is 40 finally seated in the stop slot. At this time, the parts are positioned substantially as shown in Figure 7 from which it will be apparent that the force of the spring against the washer 15 tends to hold the latch 16 firmly in the stop slot and the 45 50 55

- spring force acting against the cover plate 12 tends to bind the frame 10 tightly against the casing 2 to provide a weatherproof and insect excluding joint.
- 5 Due to the fact that screens are generally used over the lower half only of a window casing, for the purposes of the present invention they require but two fasteners for interlocking engagement with the lower pair of casing keeper elements.
- 10 For full length screens or storm windows four fasteners may be employed as shown in Figure 3. Screens and storm windows are used interchangeably with a common window casing and the complementary elements of the herein disclosed novel
- 15 fastener are permanent on the screen and storm window and on the window casing when once properly affixed thereto. The concealment of the spring and cup within the body of the frame and the general arrangement and construction of the
- 20 fastener parts provide for a simple compact fastener inexpensive to manufacture and easy to install, the installation being such that the face

of the frame is substantially devoid of unsightly projecting or objectionable fixtures.

Having thus described the invention, what is claimed is:—

Means for detachably fastening screen and storm window frames in overlapping engagement with an exterior frame of a window casing comprising keeper means carried by a part of the inner edge of said exterior frame, a cup carried by the screen or storm window frame and opening 10 out on the inner face of said frame, a cover plate closing the open end of the cup and attached to the inner face of said frame, said cover plate having an opening therein, a rod passing through the opening, a washer connected to the inner end 15 of the rod and slidably arranged in the cup, a spring encircling the rod and located between the washer and the cover plate, a latch plate connected with the outer end of the rod and having a rounded end for engaging the keeper means, 20 the opposite end being reduced in width and bowed to form a finger piece.

TREFFLE E. FOURNIER.
